COMBINATION RAILWAY PASSENGER AND FOOD SERVICE CAR BODY

Carl W. Sundberg, Bloomfield Hills, Mich., assignor to
General Steel Industries, Inc., Granite City, Ill., a
corporation of Delaware

Filed Dec. 29, 1965, Ser. No. 369

Term of patent 14 years

(Cl. D66—1)

FIG.1

Des. 209,877

PAGE 2

FIG. 2

FIG. 3

FIG. 4

FIG. 5

FIG. 6.

FIG. 7.

FIG. 8.

FIG. 1 is a perspective view, partially broken away for convenience of illustration, of a combination railway passenger and food service car interior taken along line 1—1 of FIG. 3.

FIG. 2 is a perspective view, partially broken away and with a portion of the vending section removed for convenience of illustration, of the car interior from the opposite end, taken along line 2—2 of FIG. 3.

FIG. 3 is a longitudinal vertical sectional view of the car.

FIG. 4 is a transverse vertical sectional view of the car interior along line 4—4 of FIG. 3.

FIG. 5 is a transverse vertical sectional view of the car interior along line 5—5 of FIG. 3.

FIG. 6 is an elevation view of the exterior side of the car corresponding to the interior side illustrated in FIG. 3.

FIG. 7 is an elevation view of the exterior side of the car opposite that shown in FIG. 6.

FIG. 8 is an end view of an exterior end of the car. Both exterior ends of the car are identical.

I claim:

The ornamental design for a combination railway passenger and food service car body, substantially as shown and described.
